RANDOM ACCESS DATA STORAGE MACHINE

David G. Moore, Los Gatos, Calif., assignor to International Business Machines Corporation, Armonk, N.Y., a corporation of New York

Filed Oct. 8, 1964, Ser. No. 82,088

Term of patent 14 years

(Cl. D26—5)

FIG. 1

FIG.2

FIG. 1 is a front perspective view of a random access data storage machine showing my new design; and
 FIG. 2 is a rear perspective view thereof.

The side not shown is substantially plain and unornamented.

I claim:

The ornamental design for a random access data storage machine, as shown and described.
